UNITED STATES PATENT OFFICE.

JUAN SIERRA SANTIAGO, OF SAN JUAN, PORTO RICO.

DIRECTION INDICATOR FOR VEHICLES.

Application filed October 15, 1925, Serial No. 62,496. Renewed August 17, 1927.

This invention relates to direction indicators, and more particularly to indicators for use on motor vehicles.

One of the principal objects of the invention is to provide a simple device of this character of novel construction and arrangements of parts.

Further objects will appear as the following description is read in connection with the accompanying drawings, which forms a part of this application, and in which:

Fig. 1 shows a side elevation of the device with the signal member lowered and locked in this position.

Fig. 2 shows a top elevation of Figure 1.

Fig. 3 shows a partly sectional, fragmentary side elevation of the device with the signal member in the raised position.

Signal member 10 has a multiple of apertures 20 formed by depressing tongues 11 out of the surface of said signal member, and is provided with a back cover 12 which is removably held by pins 13 to said signal member. Carried by said cover 12 is a support 25 14 provided with a lamp bulb socket 15, an electric lamp 16, and flexible leads 17.

During the daytime signal member may be used with the electric lamp turned off, but at night or in cloudy weather, it is advisable 30 to illuminate the signal member by having the lamp turned on thereby allowing rays out of apertures in said signal member damped by tongues 11. This type of signal member has been claimed in a co-pending application.

Supporting said signal member is a lever 18 rigidly fastened to hub of pinion 19 pivotally mounted by pintle screw 20 to support body 21. A segment toothed lever 22 is also 40 pivotally mounted by pintle screw 23 to support body 21, is provided with a normal position spring 24 acting within said support body, and locking rod 25 pivoted by pintle screw 26. Projecting from support body 21 is a portion having a V-shaped cut 26' into which locking rod 25 engages and locks signal member into downward position. A stop rod 27 fastened to support body 21 acts 45 against pinion 19 having some teeth missing acting as a stop to permit about 90° movement for signal member, and a chain 28 adds to the action of the stop in the horizontal position.

Supporting body 21 has a projection support 29 to a supporting rod 30 carrying a

clamp 31 for fastening to windshield frame 32 of a vehicle.

In its normal position the signal member is in the upright position. The device is operated by pressing down on handle part 60 of segment toothed lever 22 and the signal member assumes a horizontal position, and if this position is desired the lock rod 25 may be locked into cut 26. When the normal position is again desired release lock rod 65 from the cut and spring 24 returns signal member to normal position.

Having thus described my invention what I claim as new, and desire to secure by Letters Patent of the United States is, as follows:

1. A device of the class described, comprising a signal member, a support body, a pinion rotatably mounted in said support body, a lever rigidly attached to said pinion, and carrying said signal member, a segmental toothed lever pivotally mounted in said support body, and engaging said pinion, a spring acting between said segmental toothed lever and the support body, normally urging said segmental toothed lever to its uppermost position, a projection with a V-shaped cut, extending from said support body, a lock rod pivotally mounted to said segmental lever, engageable with said V-shaped cut to lock said segmental lever in its lowermost position, said pinion having a portion of its teeth removed, and a stop rod rigidly depending from said support body, and acting against the bare portion of said pinion.

2. A device of the class described associated with a windshield frame comprising a signal member, a support body, a pinion rotatably mounted in said support body, a lever rigidly attached to said pinion, and carrying said signal member, a segmental toothed lever pivotally mounted in said support body, and engaging said pinion, a spring acting between said segmental toothed lever and the support body, normally urging said segmental toothed lever to its uppermost position, a projection with a V-shaped cut, extending from said support body, a lock rod pivotally mounted to said segmental lever, engageable with said V-shaped cut to lock said segmental lever in its lowermost position, said pinion having a portion of its teeth removed, a stop rod rigidly depending from said support body, and acting against the bare portion of said pinion, and a sup-

port chain fastened at one end to said windshield frame, and at the other end to said lever carrying the signal member, to cooperate with said stop rod when the segmental lever is in its lowermost position.

3. A device of the class described associated with a windshield frame comprising a signal member, a support body, means for attaching said support body to a frame, a pinion rotatably mounted in said support body, a lever rigidly attached to said pinion, and carrying said signal member, a segmental toothed lever pivotally mounted in said support body, and engaging said pinion, a spring acting between said segmental toothed lever and the support body, normally urging said segmental toothed lever to its uppermost position, a projection with a V-shaped cut, extending from said support body, a lock rod pivotally mounted to said segmental lever, engageable with said V-shaped cut to lock said segmental lever in its lowermost position, said pinion having a portion of its teeth removed, a stop rod rigidly depending from said support body, and acting against the bare portion of said pinion, and a support chain fastened at one end to said windshield frame, and at the other end to said lever carrying the signal member, to cooperate with said rod when the segmental lever is in its lowermost position.

4. A device of the class described, comprising a signal member, a support body, a pinion rotatably mounted in said support body, a lever rigidly attached to said pinion, and carrying said signal member, a segmental toothed lever pivotally mounted in said support body, and engaging said pinion, a spring normally urging said segmental toothed lever to its uppermost position, a projection with a V-shaped cut, extending from said support body, a lock rod pivotally mounted to said segmental lever, engageable with said V-shaped cut to lock said segmental lever in its lowermost position, 35 said pinion having a portion of its teeth removed, and a stop rod rigidly depending from said support body, and acting against the bare portion of said pinion.

5. In a device of the class described, having a segmental toothed lever operatively connected to a signal member, said segmental toothed lever being pivoted to a support body, the combination of a projection extending from said support body, said projection being formed with a V-shaped cut, and a lock rod pivotally mounted to the said segmental toothed lever, said lock rod being engageable with said V-shaped cut.

In testimony whereof I have affixed my 60
signature.

JUAN SIERRA SANTIAGO.
